UNITED STATES PATENT OFFICE.

GEORGE M. ALLARD, OF SPOKANE, WASHINGTON.

GATE MECHANISM.

Application filed April 12, 1923. Serial No. 631,618.

To all whom it may concern:

Be it known that I, GEORGE M. ALLARD, a citizen of the United States, residing at Spokane, in the county of Spokane and State of Washington, have invented new and useful Improvements in Gate Mechanism, of which the following is a specification.

This invention relates to improvements in gate mechanisms especially designed for use 10 at rail road crossings.

Now in accordance with my invention, I consider the road way as a travel way, and the rail road as a travel way, the same intersecting or cross one another, and 15 my improved gate mechanism is adapted to be disposed at such intersection for the dual purpose of arresting traffic on one travel way, when the gates are in one position, and arresting traffic on the other travel way when 20 the gates are in another position. Thus, it will be seen that my device relates to that type in which the gates are never in a non-functioning position but always in a functioning position.

25 A further feature of novelty resides in means for positively moving the gates from one position to another, the return movement being by gravity.

30 A further feature of novelty resides in operating means for the gates which is wholly enclosed and concealed from view, and likewise protected from climatic interference. This feature involves a novel form of hood for the gate which moves therewith and also 35 covers a portion of the gate mechanism.

My invention has many other features of 40 novelty which will be more fully described in connection with the accompanying drawings and which will be more particularly pointed out in and by the appended claims.

In the drawings:—

Fig. 1, is a plan view diagrammatically illustrating an installation of my gate mechanism on an intersection of a road way and 45 a single track railway, two gates functioning in the dual capacity of protecting both travel ways.

Fig. 2, is a plan view showing an installation at an intersection of a road way with a 50 double track railway, wherein four gates are employed.

Fig. 3, is an enlarged sectional view on line 3—3 of Fig. 1, showing the gate in the position which it will seek by gravity.

55 Fig. 4, is a similar view showing the gate

turned ninety degrees from the position shown in Fig. 3.

Like characters of reference designate similar parts throughout the different figures of the drawings.

I will first describe the installations shown in Figs. 1 and 2, then I will describe the specific structure of the gate mechanism shown in Figs. 3 and 4, and finally, I will describe the manner of effecting operation of 60 the gates.

First referring to Fig. 1, 1 designates the roadway and 2 and 3, the rails of a railway track, these respectively travel ways intersecting as clearly indicated. I have shown 70 the fences along the railway at 4, 5, 6 and 7. In this installation, I employ two gates, with mechanism for each, and as the gate structures are alike in structure and operation, only one need be described in detail 75 although they will be generally designated by different numerals 8 and 9. The gate 8, is mounted to swing in a horizontal plane about a post structure 10, as a vertical axis, either to the full line position where it protects the railway, or to the dotted line position where it protects the roadway. Likewise, gate 9, is mounted on a post structure 11, located at the opposite side of the intersection, and about which gate 9, can swing 80 horizontally from the full line to the dotted line position. In either position, the gates are in a travel way protecting position. I have shown the fences along side the railway arranged so that when the gates are in 90 the full line position shown, they co-operate with the fences to block entrance of cattle along the rail way. When the gates are in the dotted line position, they arrest travel on the roadway 1, and open the way for 95 travel along the railway.

In the modified form shown in Fig. 2, I employ four gates, or in other words I show how four gates can be used where the "reach" would be too great for either of 100 two gates, and would tend to make them of too great weight to be readily operated. Thus, in Fig. 2, instead of disposing gate post structures at diagonally opposite corners of the intersection, I dispose gate posts 12, 13, 14 and 15, at each corner of the intersection. Post 12, has a gate 16, and respectively for the remaining posts gates 17, 18 and 19 are provided. Suitable stops 20 to 27, limit swinging movement of the gates 110

after they have reached the full or dotted line positions. I may likewise provide similar stops for gates 8 and 9, as indicated at 28 to 31. In Fig. 2, I have shown fences 32 and 33, coacting with the gates to prevent cattle from entering along the railway when the gates are in the full line position shown in Fig. 2. These gates 16 to 19, are relatively short, and thus one pair of gates can 10 jointly extend across either travel way. In this modified form, the operation is the same as in Fig. 1.

I will next refer to Figs. 3 and 4, and will describe the specific construction of the gate 15 structure.

This structure includes a post 34, rigidly mounted on a base 35. This base 35, is fixed to the bottom of a housing 36, which is sunk below the ground level with its top 37, substantially at the ground level. A supporting flange 38, may be formed integral with said post and it will be seen that this flange is disposed at an angle to the horizontal. A gate sleeve 39, is freely slideable and rotatable on said post 34, and is securely fixed to the upper member 40 of the fabricated gate 8. The exact construction of the gate is not important, and may be as shown in Fig. 3. The lower member 41, of said gate is fixed to a supporting and elevating sleeve 42, which is also freely slideable and rotatable on said post. The lower portion of sleeve 42 has a bearing flange 43, resting on flange 38, and correspondingly inclined. Said flange 43, has an arm 44, to which a cable 45, is attached. It will be noted that the top 46, of housing 37, has a sleeve 47, which surrounds the post 34, and extends slightly above the ground level. The post 34, is equipped with a hood 48, supported on the gate 8, and having its lower end 49 extending around sleeve 47 in a manner to prevent rain and snow from gaining access to housing 37.

The coaction of flanges 38 and 43, elevates gate 8, as the latter is swung ninety degrees from the full line position shown in Fig. 1 to the dotted line position, and this movement of the gate is positively effected, in a manner to be later described. I prefer to 50 positively actuate the gate from a track to a road protecting position rather than vice versa. Due to elevation of the gate, the latter, will, because of the inclined flanges, return to a track protecting position as shown in full lines, by gravity. I do not wish to be limited to this precise means as other specific means within the purview of the claims might be substituted therefor. Because the hood 48 is rigidly mounted on the 55 gate 8, it will partake of this turning and elevating position of the gate and will always shroud the same.

In Fig. 4, I have shown the gate elevated and turned and it will be noted that because the gate only moves ninety degrees,

the lowest portion of flange 43, will never reach the highest portion of flange 38, therefore, the gate will always seek to return to its initial position by gravity. Not only will the gate seek to return the level or position shown in Fig. 3, downwardly, but it will be forced to turn as it descends, and therefore it will inevitably return to the position shown in Fig. 3. If binding friction proves too great, anti-friction bearings 75 may be employed, but this is a mere matter of mechanical skill.

I will next describe the motor or motive means for swinging the gates.

The cable 45, is trained about a pulley 50, which is rotatably and vertically slideable on a spindle 51, suitably fixed in the housing 37. Shoulders 52, limit vertical movement of the pulley. The remaining end of said cable 45, is connected with the core 53, of an electric motor such as a solenoid provided with a coil 54, into which said core 53 is drawn, when circuit is closed. A stop 55, limits outward movement of said core so that the cable can never slacken sufficiently to become free from the grooved pulley 50. It will now be clear that when the solenoids are energized, the gates 8 and 9, will be positively swung from the full to the dotted line positions shown in Fig. 1, 95 and that when the solenoids are de-energized, the gates will return by gravity to the full line positions. The stops, previously described, will limit movement of the gates in either direction.

I will next describe the circuit whereby the mechanism is electrically energized and de-energized.

The section of the track extending across the intersection, is insulated off as indicated at 56. A source of current is shown at 57, and one pole thereof is connected with rails 3, by wire 58. The other pole is connected by wire 59 with one of the solenoid windings 54. A wire 60, leads from said solenoid to the solenoid for the opposite gate 8. A wire 61, leads from the gate 8 solenoid 54, to track 2. Now it will be clear that as the first wheels of a train vehicle enter the insulated section, the circuit will be closed, and both solenoids, or rather all solenoids will be energized and the gates will be swung from the full line to the dotted line positions. They will be held in the dotted line position until the wheels of the last coach leave the insulated section, whereupon, the circuit will be opened and the gates will return by gravity from the dotted line to the full line position.

To prevent burning out the solenoid coils, 125 I may interpose a resistance 62, as shown in Fig. 1. The connection 63, is shown pivoted, and an arm 64, on the core 53, may serve to shift the contact connection 63, into an open circuit position so that current will 130

flow through the resistance 62, after the gates have been moved to the dotted line position. The amount of current passing through the coils, by way of the resistance, 5 will be sufficient to retain the gates in the dotted line position after they have been moved to such position.

I do not make any claim to the precise 10 electrical circuit for energizing the sole-
noids, as the novelty of my invention resides
in the gates and the structure thereof, with
means broadly, for actuating said gates.

It is believed that the device of my in- 15 vention will be fully understood from the
foregoing description and I do not wish
to be limited thereto except for such limita-
tions as the claims may import.

I claim:

1. A gate mechanism for railway and 20 highway intersections comprising in combi-
nation, a plurality of gates normally mov-
able by gravity into a position across said
railway, and train initiated means for caus-
ing said gates to move from a position 25
across said railway into a position across
said highway and be retained in said posi-
tion until the train has passed the intersec-
tion, said means being thereupon released to
permit said gates to swing by gravity back 30
into a position across said rail way.

2. A gate mechanism for railway and 35 highway intersections comprising in combi-
nation, a plurality of gates normally mov-
able by gravity into a position across the
railway, stops for retaining said gates be-
yond such position, train initiated means 40
for causing said gates to move from a posi-
tion across said railway into a position
across said highway, and stops for limiting
movement of said gates toward said last
named position.

3. A gravity gate mechanism for intersecting travel ways comprising in combination, a post having an inclined supporting 45 flange, a gate sleeved on said post and hav-
ing a correspondingly inclined flange where-
by when said gate is turned it will be ele-
vated and will return to its initial position
when released, and train initiated means 50
for moving said gate against the action of
gravity.

4. A gravity gate mechanism for intersecting travel ways comprising in combination, a post member, a gate member turnable 55 on said post member, said members having
coacting means for elevating said gate when
the latter is turned whereby when said gate
is released it will return to its initial posi-
tion by gravity, and train initiated means 60
for moving said gate against the action of
gravity.

5. A gate mechanism for intersecting 65 travel ways comprising in combination, a
housing sunk in the ground and having a
tubular extension projecting above the
ground, a post fixedly mounted in said
housing and extending upwardly through 70
said tubular extension, a gate above the
ground and having a sleeve connection with
said post and said sleeve connection extend-
ing downwardly through said tubular ex-
tension into said housing, train initiated 75
means in said housing connected with said
sleeve connection for actuating said gate,
and a protecting hood carried by said gate
and shrouding said post and exteriorly tele-
scoping said tubular extension to prevent
rain and snow from entering said housing.

In testimony, that I claim the foregoing
as my own, I hereby affix my signature.

GEORGE M. ALLARD.
